R. W. GATEWOOD

INDICATING CAR SEAL

Filed Sept. 10, 1923

Attorney

UNITED STATES PATENT OFFICE.

RIBOURNE W. GATEWOOD, OF NORFOLK, VIRGINIA.

INDICATING CAR SEAL.

Application filed September 10, 1923. Serial No. 661,833.

To all whom it may concern:

Be it known that I, RIBOURNE W. GATEWOOD, a citizen of the United States, residing at Norfolk, in the county of Norfolk 5 and State of Virginia, have invented certain new and useful Improvements in Indicating Car Seals, of which the following is a specification.

My invention relates to indicating car 10 seals.

The object of the invention is to provide means whereby evidence will be shown if a railway car door be unlawfully opened and left so or opened and closed.

With the ordinary wire or metal strap seal, an unauthorized person may cut the wire or strap, take what goods he desires, then closing the door and by adroitly joining the two ends of the severed wire or strap, the car door will have no indication of being opened and closed. When the railway car inspector sees that the car is apparently unopened and so checks it, but on the contrary, when the car has arrived at 15 its destination or many miles away, it is discovered that some goods have been abstracted and in the meantime the thief has had plenty of time to make a "get away", while in my invention, the opening of the car door is immediately indicated so there is time to give the alarm and apprehend the culprit before he can leave the premises or dispose of the stolen goods.

In my invention I provide means where 20 the seal may not be tampered with, also acts as a lock and adapted to have the ordinary wire or strap seal applied, additionally.

Further objects and advantages will be more fully described herein and specifically 25 pointed out in the annexed claim recourse being had to the accompanying drawing forming a part of this specification in which:

Figure 1 is a portion of a box car and its 30 sliding door showing my invention applied thereto.

Figure 2 is a plan of my device detached from the car.

Figure 3 is an edge view.

Figure 4 is a front view of the main casting or block with the cover plate removed to show the channels therein.

Figure 5 is a complete front view of my invention with the hasp or latch bar in cor- 35 relative position.

Figure 6 is a cross section of the main casting and the cover plate taken on the line 1, in Figure 4.

Figure 7 is a portion of the hasp bar in plan or edge view, when arranged with a 60 joint or fulcrum near its right hand end.

Figure 8 is a plan or edge view of the latch bar or hasp showing the outer or left hand end thereof.

Figure 9 is a fragmentary section of the 65 main casting and the seal disc or check box flange shown in Figure 10.

Figure 10 is a fragmentary portion of the check box flange and the main casting or block showing the recess for the key screw. 70

Figure 11 is an end view of the socket end of the key.

Figure 12 is a side view of the key.

Figure 13 is a perspective view of the 75 check or seal disc receiver or box.

In the drawing like reference numerals indicate similar parts in all the several views:—

1 represents the car sides or body, 2 the door hangers, and 3, the sliding door as in 80 the ordinary manner.

4 is the main casting or block which is slotted to allow the latch bar or hasp 5 to transversely pass through it, as will be described hereafter. To allow for the vertical 85 motion of the car when running, I divide the bar into two parts, that at 5^a being fastened to the car door by the bolt 5^b and the main portion 5 pivoted thereto by the pin 5^c, as shown in Figures 5 and 7. 90

9^a is a cover for the block or casting 4 and is provided with a fenestration, orifice or window 6.

The block 4 and the cover plate 9^a is provided with holes 7 for the bolts or screws 8 which pass through the car sides and having the nuts, (in the case of bolts), upon the inside of the car. 95

9 is a transverse slot for the passage of the lock bar or latch 5, 9^b, Figure 5, being a wider slot to accommodate the movement of the triangular latch bar holding lug 11^b, as will be described hereafter. 100

The bar 5 is provided with a vertical flattened slot or opening 10 transversely through it for the passage of the check or seal disc, which will be mentioned later in connection with the check guideways or slots in the block 4. 105

11 is a hole in the end of the latch bar 110

or hasp 5 for passing the wire or strap of an ordinary seal in the usual manner.

11^a is a slot at right angles to the hole 11 and parallel with the slot 10 and is for the purpose of inserting a pin, (not shown), to enable the door 3 to remain closed when the car is in transit, or the triangular projection or lug 11^b, Figures 5 and 8, may be used instead, and when the bar 5 is at an angle, as shown at the left hand side of Figure 5, the lug will engage the outer edge of the block 4 and holds the door shut until the latch bar is raised. In order to adopt the latter method, it will be necessary to widen the bar slot 9 to the width 9^a, Figure 5.

12 is a slot or channel cast into the block or main casting 4 which has an inclined upper portion, and a curved central portion terminating in the vertical portion 12^a, at the bottom of which there is a rectangular orifice 13 passing entirely through the block, as shown in Figures 4 and 6. The orifice 13 is normally closed by the cover plate 9^a, on the outside of the car, and on the inside by the flange 14^a of the seal or check receiving drawer or box 14, a corresponding orifice being cut into the sides of the car so that the box 14 may be reached from the interior of the car for opening and closing the same.

15 is the indicating disc, seal or check composed of any desirable metal having suitable characters, numbers or inscriptions thereon, as may be desired.

16 is the entrance to the slot 12 and 12^a for the check 15 and when introduced therein, falls down edgewise and comes to rest on the upper edge of the latch bar 5 when the bar is in the position shown in Figure 5, the car door 3 being closed as shown in Figure 1.

The check or disc 15 then comes in alignment with the window or orifice 6 and there remains and cannot fall outwards or pass through the openings as it is slightly larger than the hole.

In the position shown in Figure 5, the check or disc 15 is visible from the outside of the car through the opening 6 and may assure the observer that the car door has not been moved.

When the car door is moved to the right the slot 10 comes under and allows the check or disc to fall, passing the straight portion of the slot 12 and into the receiving box or drawer 14 upon the inside of the car.

An employee of the railway or others, may now see that the hole is unoccupied by the check 15 and that the car door has been moved and may communicate the fact to the proper authorities and investigation made.

In Figure 4, I show by dotted lines a

modified form of check or disc channels 65 which I prefer and wherein 17 indicates a straight groove or channel and 18 a sloping entrance to the part 12^a of the slot 12, likewise, a similar straight slot 21 is provided which is opposite the first named channel and has an upper angular part 19 and a straight portion 21, the former being in staggered relation with the lower end of the angular portion 18 of the channel 17. This arrangement prevents an unauthorized person from pushing up the seal or check 15 by a pointed instrument upwards while a confederate opens the door, taking out goods, and closing the same. If such is attempted, the disc 15 will fall or roll into the angle end 19 of the slot 21 by rolling over the corner 20, Figure 4, and fall into the box or drawer 14, as before, the aperture 13, in which case would have to be extended and made longer as shown by the dotted 80 lines in Figure 4.

The check or disc receiving box 14 is slidably fitted into the opening 13 from the inside of the car and is prevented from being pushed too far by the flange or plate 14^a 90 and upon which flange there is a cast on sleeve 25 upon the inner portion of the same which has a threaded hole 23 therein for the holding screw 24, Figures 6, 9 and 10, bored in its center.

The screw 24 passes through the flange 14^a of the box 14 and partly into the main casting or block 4 and firmly secures the same.

The screw 24 is normally below the edge 100 of the sleeve 25 and the former is provided with a triangular head, as at 24, and is turned by a key or socket wrench 26 having a similar recess 28 in one end which is slightly larger than the head of the screw so that 105 it may fit easily over it.

By this means, the screw 24 cannot be turned by any but its key or operated in any other way to release the check box 14 unless the authorized key be used if the car 110 is left open when upon a siding.

My device is cheap and may be applied to any car and car door easily and quickly.

I claim:

In combination with a car and its door, 115 of a receptacle on the car and provided with an opening or window in the front portion thereof, a latch bar or hasp passing through said receptacle and movably and slidably positioned therein, a disc or seal normally resting upon said latch bar and visible from the exterior of the car, and means for dropping said disc or seal out of view by the movement of said latch bar.

In testimony whereof I have hereunto affixed my signature.

RIBOURNE W. GATEWOOD.
